UNITED STATES PATENT OFFICE.

CHARLES E. LINNIG, OF PERU, ILLINOIS.

ENGRAVER'S CLAMP.

1,420,715.

Specification of Letters Patent. Patented June 27, 1922.

Application filed August 6, 1921. Serial No. 490,426.

To all whom it may concern:

Be it known that I, CHARLES E. LINNIG, a citizen of the United States, residing in the city of Peru, county of La Salle, and 5 State of Illinois, have invented certain new and useful Improvements in Engravers' Clamps, of which the following is a specification.

My invention relates to improvements in 10 engraver's clamp and has for its object the production of an engraver's clamp having a series of correlating removable and interchangeable jaws and in which the clamping mechanism can be so adjusted to allow a very 15 extended angular movement, both sidewise as well as vertically, so that all manner of work may be successfully held in a substantial manner while the work is done on the part located in the jaws.

20 These objects, together with other objects readily apparent to those skilled in the art, I attain by the construction illustrated in the accompanying drawings, in which—

Fig. 1 is a top view of my clamp,
25 Fig. 2 is a side view of my clamp,
Fig. 3 is a front view of my clamp,
Fig. 4 is a partial end view of Figs. 1 and 2,

30 Fig. 5 is a cross-sectional view along a line A—B, Fig. 1,

Fig. 6 is a partial cross-sectional view of Fig. 3 along a line C—D,

35 Fig. 7 is a partial end view showing the guiding means I employ to guide the movable part of my invention,

Fig. 8 is an enlarged partial cross-sectional view of Fig. 1 along the line A—B, showing the fastening means employed,

40 Fig. 9 is an end view of Fig. 8,
Fig. 10 is a top view of a registering piece for adapting my system of interchangeable jaws to the ordinary engraver's clamp now in use,

Fig. 11 is a side view of Fig. 10,
45 Fig. 12 is an end view of Fig. 10,

Fig. 13 is a top view of one of my interchangeable jaw pieces for holding spoons or similarly shaped articles,

50 Fig. 14 is a side view of Fig. 13,
Fig. 15 is an end view of Fig. 13,

Fig. 16 is a top view of a jaw-piece for holding buttons and the like,

Fig. 17 is a side view of Fig. 16,

Fig. 18 is an end view of Fig. 16,

Fig. 19 is a top view of a registering piece 55 that permits the use of the holding parts shown in Figs. 16, 17 and 18 with the universal head of all clamps,

Fig. 20 is a side view of Fig. 19,

Fig. 21 is a top view of an insert for the 60 jaw-piece shown in Figs. 16, 17 and 18,

Fig. 22 is a side view of Fig. 21,

Fig. 23 is a top view of an insert for the 65 jaw-piece shown in Figs. 16, 17 and 18,

Fig. 24 is a side view of Fig. 23,

Fig. 25 is a top view of an insert for the 70 jaw-piece shown in Figs. 16, 17 and 18,

Fig. 26 is a side view of Fig. 25,

Fig. 27 is a partial cross-sectional view of 75 Fig. 16 along a line E—F,

Fig. 28 is a partial cross-sectional view of Fig. 16 along a line G—H,

Fig. 29 is a top view of my universal head 80 hole jaw pieces,

Fig. 30 is a side view of same,

Fig. 31 is an end view of Fig. 30 showing 85 a partial section along a line I—J of Fig. 29,

Fig. 32 is a top view of a jaw-piece for holding special and peculiarly shaped articles,

80 Fig. 33 is a side view of Fig. 32,

Fig. 34 is an end view of Fig. 32,

Fig. 35 is a side view of a turntable on which my clamp is mounted and by means of which it can be adjusted to any angular 85 position to make the working convenient,

Fig. 36 is a top view of Fig. 35.

Similar numerals represent similar parts throughout the several views. 1 represents the base of my clamp, which has a screw 2 90 that has the shoulders shown, which screw is journaled in bearings 3 and 4 fastened to 1. Screw 2 has a knurled head 5 by means of which it is rotated with the fingers. The shoulders shown on screw 2 prevent it from 95 moving endwise. Mounted on screw 2 is a nut 6 having a projection 7 (see Fig. 5) which engages with the movable or rear part 8 of my clamp. Part 8 has two conical apertures 9 and 10 (see Fig. 1) through which 100 pass the rods 11 and 12, which are fastened to and project from the stationary part 13 of my clamp, which part 13 is fastened to or projects from part 1 as shown. Attached to but adjustably connected with movable 105 part 8 in the manner shown (see Figs. 5 and 8) is a screw 14 which passes through an aperture in 13 and has the thumb or wing

2

nut 15 and a washer 22, by means of which the movable part 8 is moved to and from the part 13. It will be seen that screw 2 with its nut 6 having the projection 7, which 5 engages the lower part of 8 forms a stop for said part 8, said stop being located at the base of 8, so that when the wing nut 15 draws the part 8 forward, said part 8 will tip so that the upper of part 8, or part 16, 10 will be closer to the upper part of 13, or part 17, thus giving the jaw parts 18 and 19, which register in 17 and 16, a very powerful gripping action. Parts 16 and 17 in my clamp are parts fastened to parts 8 and 15 respectively and so formed as shown (see Figs. 1, 2 and 5) that they have a socket part 20 and part 21 projecting into said socket, the two parts together forming a registering means whereby a large number 20 of different shaped jaws, parts 18 and 19, can be interchangeably employed to hold the various complicated parts necessary to be held in the engraver's art. Part 13 has two screws 23 and 24 spaced close to its outer 25 ends which register on plates 25 in 8, by means of which the movable part 8 can be positioned so that it will be at angle to the part 13 instead of parallel with it, which enables my clamp to hold angular articles. In 30 order that my system of jaw-pieces can be used with the clamps now in use, I use the registering piece shown in Figs. 10, 11 and 12, whose upper or holding part is the same as that above described except that it has a 35 bottom plate 26 fastened to a plate 27, by means of projecting pins 28 and 29, which pins register with holes in the universal head of said clamps. It is evident from the above described registering piece that my system 40 of jaws can be adapted for use with the clamps now in use. One of the jaw-pieces used for such articles as spoon handles, etc., is shown in Figs. 13, 14 and 15, in which 30 is the base of the jaw-piece having the 45 registering and locating slot 31 which register with the parts 20 and 21 of my clamp, as above described, and a part 32 of a suitable soft material fastened to the base 30 and having the suitably shaped cavity shown. 50 One of the jaw-pieces used for holding such articles as buttons etc. is shown in Figs. 16, 17 and 18 and 27 and 28 comprises the usual base 30 and registering slots 31 and shaped as shown, having a soft metal part 55 35 fastened to same on a plate 36, as shown. Beneath plate 36 is another part 37 which has a shouldered part 38 raised from same, which has the threaded aperture shown for screw 39. Journaled on shouldered part 38 60 is a gear wheel 40, which meshes with a gear wheel 41, which is fastened to a shouldered cylindrical nut part 42, which is journaled in an aperture in part 37. Shouldered cylindrical part 42 has the threaded aperture 65 shown, into which fits the threaded rod 43,

which passes through an aperture in plate 36 and is fastened to a smaller suitably shaped and guided piece 44, which is raised and lowered by means of the threaded rod 43 whenever the gear 40 is suitably rotated 70 when pressed with the fingers, since when 40 is rotated, it being in mesh with 41, which turns the nut 42, which raises or lowers the piece 44, which is so guided as shown that it cannot rotate. By these means, above described, the work can be suitably positioned to properly hold it in the metal parts 35. The soft metal part 35 is so shaped that a set of secondary jaw parts, shown in Figs. 21, 22, 23 and 24 and 25 and 26 can be inserted 75 to handle different shaped articles. My universal hole head jaw-piece complete is shown in Figs. 29, 30 and 31 and is of the shape shown, each part having the usual base 30 and registering slots 31 and has a plurality of holes 33 in the top of same. Another one of the jaw-pieces is shown in Figs. 32, 33 and 34 and is similar to that shown in Figs. 13, 14 and 15 except that it is formed entirely of wood or soft metal (it having no 80 part 32 of different material) and that it has two holes 34, by means of which it can be used with my universal hole head jaw-piece or with similar parts of clamps now in use. The turntable or fixture I use for mounting 85 my clamp on is shown in Figs. 35 and 36 and which comprises a partial ball 35 shaped as shown, having a part 36 rotatably mounted on same by means of pin 37. Part 36 has 90 slidably mounted in it a part 38 to which 100 the base of my clamp is fastened by means of the screws shown at 39. Part 38 is moved by means of the shouldered screw 40, which is suitably mounted in the part 36 by means of the plates 41. The turntable is held in 105 various positions by means of the so-called leather doughnut 42, indicated in dotted lines in Fig. 35 and which rests on the work bench.

In use my clamp is operated as follows— 110 The proper jaw-pieces for such an article as a button are selected and these jaws registered into the corresponding part of the clamp and the toe-piece on the lower adjusting screw is set so as to give the jaw-pieces the required amount of angle or tilt and the clamp is then nearly closed on the button. The button then is raised or adjusted to the proper position by means of the 115 adjusting screws on the button holding jaws as above described and then the thumb or wing nut is turned to clamp the jaws together. Should any sidewise angular adjustment of the jaws be required, this is taken care of by means of the two screws 120 mentioned at each end of the stationary projection on the clamp.

From the above description it will be seen that I have invented an engraver's clamp 125 having a series of correlating or inter- 130

changeable jaws to handle all manner of work and in which the clamping mechanism can be adjusted to allow a very extended angular movement, both sidewise as well as vertically and I have accomplished same in a very simple and inexpensive manner.

It will be understood, of course, that while I have here shown one form of my invention, I do not wish to limit it to the exact form shown, but desire to have it taken in a sense illustrative of any or all forms of my inventions that come fairly within the scope of my claims.

15 I claim:-

1. In an engraver's clamp, a base, a stationary jaw projecting therefrom, a jaw movably mounted thereon with means for positioning said movably mounted jaw in combination with independent means mounted in said base for tilting said movable jaw both vertically and sidewise relatively to said stationary jaw.

2. In an engraver's clamp, a base, a stationary jaw mounted on same, guiding means projecting from said jaw, an auxiliary jaw movably mounted on said guiding means and said base, means for moving said jaw in combination with independent means for angularly positioning said jaw both vertically and sidewise relatively to said stationary jaw.

3. In an engraver's clamp, a base, a stationary jaw projecting therefrom, a jaw movably mounted thereon, with means for moving said movably mounted jaw along said base and in combination with adjustable means mounted in said base for independently positioning said movably mounted jaw into angular position relatively to said stationary jaw.

4. In an engraver's clamp, a base, a stationary jaw having an aperture mounted on said base, a plurality of rods projecting from said jaw, an auxiliary jaw movably mounted on said rods, a threaded bolt loosely attached to said auxiliary jaw and passing through the aperture in said stationary jaw, a nut on said bolt, a threaded bolt rotatably mounted in said base and a nut having a projection therefrom which engages said auxiliary jaw, with auxiliary means for securing said movable jaw in angular positions relative to said stationary jaw.

5. In an engraver's clamp, a base, a projection from said base having registering means comprising a suitably formed member having a plurality of projecting edges, a jaw inserted in said registering means, an auxiliary block having similar registering means, a jaw inserted in same, means for moving said block to and fro from said projection and means for positioning said auxiliary block.

6. In an engraver's clamp, a base, a projection from said base having suitable registering means comprising a suitably formed member having a plurality of projecting edges, a jaw having similar registering means movably mounted on said base in combination with a plurality of suitably shaped blocks having co-operative registering means.

7. In an engraver's clamp, a base, a projection from said base having suitable registering means comprising a suitably formed member having a plurality of projecting edges, a jaw having similar registering means movably mounted on said base with means for positioning said movable jaw in combination with a plurality of suitably shaped blocks having co-operative registering means.

8. In an engraver's clamp, a base, a projection from said base having suitable registering means comprising a suitably formed member having a plurality of projecting edges, a jaw having similar registering means movably mounted on said base with means for positioning said movable jaw in combination with a plurality of suitably shaped blocks having means which register and coact with said registering means.

9. In an engraver's clamp, a base, a projection from said base having suitable registering means comprising a suitably formed member having a plurality of projecting edges, a jaw having similar registering means movably mounted on said base with means for positioning said movable jaw in combination with a plurality of suitably shaped blocks having means which register and coact with said registering means, and positioning means within the said blocks.

10. In an engraver's clamp, a base, a projection from said base having suitable registering means comprising a suitably formed member having a plurality of projecting edges, a jaw having similar registering means movably mounted on said base with means for positioning said movable jaw in combination with a plurality of suitably shaped blocks having co-operative registering means, and positioning means within the said blocks.

11. In an engraver's clamp, a base, a projection from said base having suitable registering means, a jaw having similar registering means movably mounted on said base with means for positioning said movable jaw in combination with a plurality of suitably shaped blocks having co-operative registering means, and positioning means within the said blocks comprising a plate, a screw fastened to said plate, a nut mounted on said screw, a gear wheel fastened to said nut and a second gear wheel journaled in said block meshing with the above mentioned gear wheel.

12. In an engraver's clamp, a base, a projection from said base having suitable reg-

registering means comprising a suitably formed member having a plurality of projection edges, a jaw having similar registering means movably mounted on said base with means for positioning said movable jaw in combination with a plurality of suitably shaped blocks having co-operative registering

means, with means for inserting suitable holding devices and positioning means within said blocks.

CHARLES E. LINNIG.
